Isaac T. Smith Inventor

United States Patent Office.

ISAAC T. SMITH, OF RICHMOND, VIRGINIA.

Letters Patent No. 100,201, dated February 22, 1870.

IMPROVED BRAKE AND RATCHET FOR ELEVATING AND LOWERING BUCKETS.

The Schedule referred to in these Letters Patent and making part of the same

To all whom it may concern:

Be it known that I, ISAAC T. SMITH, of Richmond, Virginia, have invented a new and useful Improvement in a Combined Brake and Ratchet used for Lowering Well-Buckets and for other similar purposes; and I do hereby declare that the following is a full and exact description thereof, reference being had to the accompanying drawings and to the letters of reference marked thereon.

The nature of my invention consists in having, in addition to the brake-wheel and ratchet-teeth on the inside of the same as before used, an additional set of segments of a rim a sufficient distance apart to allow the pawl to pass through when the brake is applied for lowering, so that after the brake-wheel has acquired an accelerated motion from the descent of the bucket or other weight being lowered, the pawl cannot again fall into the ratchet-wheel until the velocity has been arrested by the proper use of the brake-lever, or from its full descent. Then it will resume its position as at first, in contact with the ratchet-wheel teeth.

To enable others skilled in the arts to make and use my invention, I will describe its construction and operation.

I describe the construction as applied to a common windlass for drawing water, or as used in connection with H. M. Smith's patent of 1866.

Construct curb A with caps B B.

Make windlass C on the end hand brake-wheel D, which I make in this case about eight inches diameter with one and one-half inch face for brake-pad.

This rim projects one and one-quarter inch from the

flange supporting it, and has ratchet-teeth on the interior surface, as shown, Figures 2 and 3.

Inside of this ratchet, leaving a clear space of three-eighths of an inch, I attach as many teeth or segments as there are ratchet-teeth marked 1, 2, 3, 4, 5, 6.

These are attached to the main flange, and project even with the first brake and ratchet-wheel.

The brake-lever E, I make of wrought or malleable iron, Figure 4, perspective, showing handle F, journal G, pad H, pawl I.

When the pawl is applied to the brake-wheel, the pawl I should just clear the inside of the segments 1, 2, 3, 4, 5, 6.

When at rest the pawl I rests in the ratchet, by reason of the weight of the handle.

To operate, raise the handle F, which throws the pawl from the ratchet and through the space between the segments. Then the bucket or weight will be lowered at the will of the operator, and if, by accident, the handle should be dropped, the pawl cannot fall into the ratchet.

What I claim as my invention, and desire to secure by Letters Patent, is—

The interior segmented rim upon the ratchet-wheel, to prevent the pawl from falling back into the ratchet whilst in rapid motion, and thus preventing accidents, as above described and set forth.

I. T. SMITH.
